[57] CLAIM

The ornamental design for a traveler's alarm clock compact, substantially as shown and described.

DESCRIPTION

FIG. 1 is a front perspective view of a traveler's alarm clock compact showing my new design in the closed position;

FIG. 2 is a rear perspective view thereof;

FIG. 3 is a top plan view thereof, the bottom being a mirror image thereto;

FIG. 4 is a front perspective view thereof in the open position, the broken line depiction of a photograph being environmental and forming no part of the claimed design.

Fig. 1.

Fig. 2.

Fig. 3.

Fig. 4.
